UNITED STATES PATENT OFFICE.

WILLIAM K. TWOMEY, OF CHICAGO, ILLINOIS.

BURNER.

1,167,446.

Specification of Letters Patent. Patented Jan. 11, 1916.

Application filed December 12, 1914. Serial No. 876,997.

To all whom it may concern:

Be it known that I, WILLIAM K. TWOMEY, a citizen of the United States, residing at Chicago, in the county of Cook and State 5 of Illinois, have invented certain new and useful Improvements in Burners, of which the following is a specification.

My present invention relates to gas burners, and has for its principal object the provision of a burner which will cause the complete combustion of the gaseous mixture so that the resulting products of the combustion will be substantially odorless and have beneficial sterilizing properties.

15 The salient feature of the invention resides in so constructing the burner that the gaseous mixture is treated to successive combustions, with intermediate treatment to render such series of burnings possible.

20 A further object of the invention is the production of a burner of this general character which shall be simple in construction, economical to manufacture, and which will comprise few parts, unlikely to become damaged or deranged.

25 The invention is susceptible of embodiment in burners of various kinds adapted for different purposes, and in order that the features of construction of a burner incorporating the invention may be understood by those skilled in the art, I have illustrated a burner of this kind suitable for the heating of a room, with the products of combustion delivered into the room, which is not 30 objectionable in a burner of this kind because the burned gases are practically odorless, and may be employed for therapeutic purposes because of their sterilizing qualities.

35 In the accompanying drawing illustrating such a burner, which forms a part of this specification, Figure 1 is a central, vertical cross-section through the structure; and Fig. 2 is a vertical, longitudinal section on 40 line 2—2 of Fig. 1, the parts being viewed in the direction indicated by the arrows.

45 In this improved and novel construction, a primary burner 10 is provided, having the usual mixing tube 11, to which gas is delivered through the pipe 12, the air being introduced through the opening 13, as is customary in constructions of this general type. This burner comprises a piece of metal 50 of suitable shape, perforated with holes,

through which this initial mixture of gas 55 and air passes before ignition.

The structure also comprises a base 14 supported on suitable feet or legs 15, 15, and has a central opening 16, through which the upwardly bent end of the tube 11 extends, 60 as is clearly illustrated. Such base is equipped with two bent-bar supports or standards 17, 17, on which rests a centrally apertured plate 18, through the hole 19 of which the tube 11 projects, as shown. A pressure-control box 20, open at the bottom and top, 65 rests on the plate 18, inclosing the burner 10, and has its interior in communication with the outside atmosphere by reason of the aperture 19. This hollow, rectangular box, 70 at its top edges, has the short, upstanding spacing lugs 21, 21, on which a cover plate 22 rests, providing two jet-openings or slots 23, 23, at the opposite ends of the box, beneath the cover plate.

75 A rectangular, hollow casing 24, with an open bottom, also rests on the plate 18 and is of substantially the same width as the box 20, snugly fitting over the latter, as illustrated in Fig. 1. This casing, however, is 80 considerably longer than the box 20, as shown, providing beneath a grid or grille 25 a pair of compartments or chambers 26, 26, at the opposite ends of the control box. This grid or grille may be composed of a 85 plurality of overlying, longitudinal and transverse rods or wires with intervening apertures or spaces, such grid dividing the interior space of the casing 24 into a lower and an upper chamber 27. At its front, 90 upper edge, the casing 24 is supplied with a jet-opening or discharge-slot 28, at which the final combustion of the gaseous mixture occurs.

95 The entire burner is incased or contained within a housing 29, open at the front for the discharge of the heat, and equipped with an inclined wall 30 above the burner, which protects the flames at the jet 28 from unduly strong currents of air. Obviously, this 100 screen or wall may, if desired, be covered with asbestos or similar material, against which the flames may play.

105 The operation of this burner occurs substantially as follows: The constituents of the mixture of gas and air become thoroughly intermixed in passing through the tube or pipe 11 to the burner 10, and as

such gaseous mixture escapes through the holes of the burner, it is burned, the oxygen for carrying on the combustion being supplied in part by the air mixed with the gas, and by the external air drawn in through the aperture 19, whereby a complete combustion of all elements of the mixture then capable of combustion is effected. The control box 20, preferably made of cast-iron, is, 5 as is illustrated, relatively small, so that the flames from the burner-jets impinge against its walls, heating the box to a low red heat. This box also performs the useful function of steadyng or equalizing the more or less variable pressure of the gas, and constitutes a pressure-regulating chamber in 10 which the products of combustion are heated and intimately mixed with the air entering through the opening 19, the playing 15 of the flames on the surfaces of the box acting to break up the products of combustion to facilitate such mixture with the air. Such gaseous mixture, as it escapes from the jet-openings or slots 23, is again burned, the 20 flames being in the chambers 26, 26, as will be readily understood. The swirling of the 25 gases in these chambers, the changing of their direction of travel, and their temporary retention in these chambers by the grid 30 subjects the gaseous mixture additionally to the heat of the control box 20, bringing about a further admixture of the gaseous elements preparatory to additional combustion. The mixture then passes up 35 through the interstices or apertures of the heated grid 25, which causes their subdivision into relatively small jets, each of which is heated by the grid. Then these jets are permitted to combine again in the 40 chamber 27, in which there may or may not be a spasmodic or intermittent burning of the lighter gases. From this chamber the heated mixture escapes through the jet or slot 28, at which it is again burned in a steady 45 blue flame, the combustion of which may or may not be assisted by the oxygen of the external air. The issuing products from these successive combustions are practically and substantially free from odor, and by 50 reason of the heat to which they have been subjected, they are free from bacteria and possess sterilizing characteristics or therapeutic properties. Stated differently, the improved and novel construction of burner 55 provides a tortuous or baffled passage through it, through which the gaseous mixture passes, such passage at various points being restricted or contracted so that the mixture may be subjected to a succession of 60 combustions. The retarded transit of the mixture through the burner results in its more or less prolonged heating, and the peculiar structural features of the burner construction described above cause the intimate intermixture of the gaseous ingredients

after each burning, preliminary to the next combustion.

While I have herein described a particular embodiment of this invention, it is to be understood that the mechanical characteristics of the burner may be modified within comparatively wide limits without departure from the substance of the invention and still retain all of its substantial advantages. For this reason, the appended 70 claims should not be limited and restricted in their scope to the particular style of burner illustrated and described, as this burner represents merely one preferred embodiment of the invention.

In this application I have referred to the control-box as of hollow rectangular form, but the shape of this box is largely immaterial and may take any other convenient form.

The method of burning gas disclosed in this application is claimed in my co-pending case Serial No. 876,998, filed December 12, 1914.

I claim:

1. In a device of the character described, the combination of three burners arranged in series to compel the gaseous mixture to pass successively through them, and means to supply the total air of the mixture to 95 the flame of the initial burner, whereby the mixture may be burned at each burner, substantially as described.

2. In a device of the character described, the combination of three burners, the outer 100 one inclosing the other two, and the intermediate one inclosing the inner one, whereby the gaseous mixture is compelled to pass successively through the burners, at each of which combustion may take place, 105 and means to supply the total air of the mixture to the flame of the initial burner, substantially as described.

3. In a device of the character described, the combination of four burners arranged 110 in series, compelling the gaseous mixture to pass successively through them, whereby the mixture may be burned at each burner, and means to supply the total air of the mixture to the flame of the initial burner, substantially as described.

4. In a device of the character described, the combination of a burner, and a box provided with a jet-opening, inclosing said burner and of such size that the flames of the burner impinge on the box-walls, the gaseous mixture being adapted to burn both at the burner and at the jet-opening, the total air of the gaseous mixture being supplied to the flame of said burner, substantially as described.

5. In a device of the character described, the combination of a burner, and an apertured box provided with a jet-opening, inclosing said burner, the gaseous mixture be-

- ing adapted to burn both at the burner and at the jet-opening of the box, the outside air entering the box through the aperture of the latter, whereby the total air of the mixture is supplied to the flame of the burner, substantially as described.
6. In a device of the character described, the combination of a burner, and an apertured box provided with a jet-opening inclosing said burner, the box being of such size that the flames of the burner impinge on the box walls, the gaseous mixture being adapted to burn both at the burner and at the jet-opening, outside air having access to the interior of the box through the aperture of the latter, whereby the total air of the mixture is supplied to the flame of the burner, substantially as described.
7. In a device of the character described, the combination of a primary burner, a box provided with a jet-opening inclosing such burner, and a casing having a jet-opening inclosing said box and primary burner, whereby the gaseous mixture is adapted to pass successively through the burner, the box and its jet-opening, and the casing and its jet-opening, and to be burned at the burner and at each of said jet-openings, the total air for the gaseous mixture being supplied to the flame of the primary burner, substantially as described.
8. In a device of the character described, the combination of a primary burner, a box provided with a jet-opening inclosing said burner and of such size that the flames of the burner impinge upon the box-walls, and a casing having a jet-opening inclosing said box and primary burner, whereby the gaseous mixture is adapted to pass successively through the burner, the box and its jet-opening, and the casing and its jet-opening, and be burned at the burner and at each of said jet-openings, the total air for the gaseous mixture being supplied to the flame of the primary burner, substantially as described.
9. In a device of the character described, the combination of a primary burner, a relatively small control-box inclosing said burner and provided with a jet-opening, said control box steadyng and equalizing the pressure, and a casing having a jet-opening inclosing said box and primary burner, whereby the gaseous mixture is adapted to pass successively through the burner, the box and its jet-opening, and the casing and its jet-opening, and to be burned at the burner and at each of said jet-openings, the total air for the gaseous mixture being supplied to the flame of the primary burner, substantially as described.
10. In a device of the character described, the combination of a primary burner, a box provided with a jet-opening inclosing said burner, said box having an air-admission
- opening for the entrance of the outside air, and a casing having a jet-opening inclosing said box and primary burner, whereby the gaseous mixture is adapted to pass successively through the burner, the box and its jet-opening, and the casing and its jet-opening, and to be burned at the burner and at each of said jet-openings, the total air for the gaseous mixture being supplied to the flame of the primary burner, substantially as described.
11. In a device of the character described, the combination of a primary burner, a box provided with a jet-opening inclosing said burner and of such size that the flames of the burner impinge upon the box-walls, said box having an air-admission opening for the entrance of the outside air, and a casing having a jet-opening inclosing said box and primary burner, whereby the gaseous mixture is adapted to pass successively through the burner, the box and its jet-opening, and the casing and its jet-opening, and to be burned at the burner and at each of said jet-openings, the total air for the gaseous mixture being supplied to the flame of the primary burner, substantially as described.
12. In a device of the character described, the combination of a primary burner, a relatively small control-box to steady and equalize the pressure, inclosing said burner, said box having an air-admission opening for the entrance of outside air, and a casing having a jet-opening, inclosing said box and primary burner, whereby the gaseous mixture is adapted to pass successively through the burner, the box and its jet-opening, and the casing and its jet-opening, and to be burned at the burner and at each of said jet-openings, the total air for the gaseous mixture being supplied to the flame of the primary burner, substantially as described.
13. In a device of the character described, the combination of a primary burner, a box provided with a jet-opening, inclosing said burner, a casing having a jet-opening, inclosing said box and primary burner, and a grid in said casing between said box and casing jet-opening, whereby the gaseous mixture is adapted to pass successively through the burner, the box and its jet-opening, and the casing and its jet-opening, and be burned at the burner and at each of said jet-openings, and also be subdivided into relatively small bodies as it passes through said grid, the total air for the gaseous mixture being supplied to the flame of the primary burner, substantially as described.
14. In a device of the character described, the combination of a primary burner, a box provided with a jet-opening, inclosing said burner and of such size that the flames of the burner impinge on the box-walls, a casing having a jet-opening, inclosing said box

and primary burner, and a grid in said casing between said box and said casing jet-opening, whereby the gaseous mixture is adapted to pass successively through the burner, the box and its jet-opening, the casing and its grid and jet-opening, and be burned at the burner and at each of said jet-openings, the body of gaseous mixture being divided into relatively small parts as it passes through said grid, the total air for the gaseous mixture being supplied to the flame of the primary burner, substantially as described.

15. In a device of the character described, the combination of a primary burner, a relatively small control-box to steady and equalize the pressure, inclosing said burner and provided with a jet-opening, a casing having a jet-opening, inclosing said box and primary burner, and a grid in said casing between said box and casing jet-opening, whereby the gaseous mixture is adapted to pass successively through the burner, the box and its jet-opening, the casing and its grid and jet-opening, and be burned at the burner and at each of said jet-openings, such gaseous mixture being divided into relatively small parts as it passes through the grid, the total air for the gaseous mixture being supplied to the flame of the primary burner, substantially as described.

16. In a device of the character described, the combination of a primary burner, a box inclosing said burner and provided with a jet-opening and an air-admission opening for the entrance of the external air, a casing having a jet-opening, inclosing said box and primary burner, and a grid in said casing between the box and casing jet-opening, whereby the gaseous mixture is adapted to pass successively through the burner, box and casing, and be burned at the burner and at each of said jet-openings, such gaseous mixture being divided into relatively small parts as it passes through said grid, the total air for the gaseous mixture being supplied to the flame of the primary burner, substantially as described.

17. In a device of the character described, the combination of a primary burner, a relatively small control-box inclosing said burner and adapted to steady and equalize the pressure, the control box being of such size that the flames of the burner impinge on the box-walls, a casing having a jet-opening, inclosing said box and primary burner, and a grid in said casing between said box and casing jet-opening, whereby the gaseous mixture is adapted to pass successively through the burner, the control box, and the casing, and be burned at the burner and at

each of said jet-openings, the gaseous mixture being divided into relatively small parts as it passes through said grid, the total air for the gaseous mixture being supplied to the flame of the primary burner, substantially as described.

18. A burner structure of the character described, having a baffled passage therethrough for the gaseous mixture, such passage being restricted at successive points, forming jet-openings at which the mixture is successively burned, the total air for the gaseous mixture being supplied to the flame of the primary burner, substantially as described.

19. A burner structure of the character described, having a passage therethrough for the transit of the gaseous mixture, and having means permitting the burning of the mixture at a plurality of successive points, such passage being constructed to retard the movement of the gaseous mixture through it, whereby to subject the mixture to the heat of the heated burner parts between the successive combustions, the total air for the gaseous mixture being supplied to the flame of the primary burner, substantially as described.

20. In a burner construction of the character described, the combination of a casing, a grid in said casing, a burner, and means to supply a gaseous mixture to said burner, the grid and burner being positioned so that the products of combustion from the burner, pass through the grid, said grid being composed of a plurality of crossing rods whose bottom surfaces are transversely curved.

21. In a burner construction of the character described, the combination of a casing, a grid in said casing, a burner, and means to supply a gaseous mixture to said burner, the said grid and burner being positioned so that the products of combustion from the burner pass through the grid, said grid being composed of a plurality of crossing rods whose top and bottom surfaces are transversely curved.

22. In a burner construction of the character described, the combination of a casing, a grid in said casing, a burner, and means to supply a gaseous mixture to said burner, the said grid and burner being positioned so that the products of combustion from the burner pass through the grid, said grid being composed of a plurality of crossing rods whose top, bottom and side surfaces are transversely curved.
